UNITED STATES PATENT OFFICE

ARTHUR HILL, OF CLEVELAND, OHIO

REDUCING VALVE

Application filed April 12, 1928. Serial No. 269,355.

My invention relates to pressure reducing valves and more particularly to automatic pressure reducing valves such as generally used for reducing the pressure between a high pressure supply source (steam, gas, air or water) and a number of low pressure working units and tanks connected therewith and fed thereby.

The object of my invention is a new valve unit readily adjustable to any desired pressure in which the movable parts without sticking readily correspond to very slight pressure variations so that a predetermined lower pressure can practically be maintained unvaryingly.

A further object of my invention is to provide a reducing valve unit of simple and sturdy construction with a main passage controlled by a piston rectangularly arranged to said passage and including communicating means for opening and closing said main passage.

Still further objects of my invention will more readily be understood as described in the following description of the drawings and as called for in the claims.

In the accompanying drawings, Fig. 1 is a plan view of my reducing valve and Fig. 2 a longitudinal section partly in elevation on line 2—2 of Fig. 1. Fig. 3 is a cross section on line 3—3 of Fig. 2, showing the by-pass in cross section. Fig. 4 is a cross section on line 4—4 of Fig. 2, and Fig. 5 is a cross section on line 5—5 of Fig. 2 showing the valve body in side elevation and Fig. 6 is a side elevation of the piston member.

As shown, the main body or casing 2 of my reducing valve embodies a cylindrical chamber 3 closed at 4 and open at 5 and said body 2 is provided with integral oppositely arranged and outwardly screw-threaded extensions 6 and 7, adapted to be connected to pipes. Extensions 6 and 7 include openings 8 and 9 rectangularly arranged to the main axis of chamber 3, so that said extensions 6 and 7 form outlet and inlet respectively for the valve unit. While opening 9 is of circular cross section, opening 8 is of oblong shape as shown at 10 for a purpose later to be described.

A piston member (see Fig. 6) 12 slidably confined within chamber 3 covers both said openings 8 and 9 and is externally grooved at 14 to provide a communicating space between inlet and outlet openings 8 and 9, when said grooved portion 14 is aligned therewith, so that a fluid or air stream may freely pass through valve body 2. Piston member 12 is hollow at both ends and provided with a tongue portion 13 at one side, engaging the closed side 4 of body 2 to permit alignment of grooved portion 14 with holes 8 and 9 when said valve is not operated. Casing 2 also shows a communicating opening or by-pass 15 connecting 9 over the closed end of body 2 with the corresponding hollow chamber 16 of piston 12 so that any back pressure in outlet opening 9 is communicated through by-pass 15 to chamber 16 and tends to move piston 12 until grooved portion 14 of said piston is moved out of alignment with inlet and outlet openings 8 and 9, and thereby the source of supply is cut off.

To counteract such movement piston 12 is yielding held by a weighted beam 17 pivotally supported by integral ears 18 of body 2. Beam 17 includes a downwardly extending lever portion 19 of yoke-shaped form at 20 and is slotted at 21 for sliding engagement with a pin 22 rigidly connected by a rod 23 with piston 12, so that any lateral movement or shifting of piston 12 is counteracted by beam 17. As shown a weight 24 is slidably supported on beam 17 and such weight may be shifted by turning of a screw-rod 25 rotatably confined within beam 17 and screw-connected with said weight 24. A scale 26 on beam 17 indicates the amount of the shifting of said weight 24 and such a scale may be divided to indicate the pressure to which the valve is set.

The operation of the valve is absolutely and automatically controlled by the movements of the piston 12, but assuming that the valve is shifted and thereby closed the high pressure on the intake side opening 8 tends to press the piston against the outlet side thereby increasing the friction and decreasing the efficiency of the valve. To

5 avoid such action opening 8 is of oblong cross-section at 10 about twice the diameter of the outlet and furthermore grooved portion 14 is of piston 12 is at the outlet side at 27 approximately twice the width of the grooved portion at the intake side at 28. Such dimensions safeguard a free floating of the piston within chamber 3 under all conditions and prohibit any sticking of the piston 10 by extensive one-sided pressure of said piston against the wall of chamber 3. Piston 12 may also carry piston rings 30 to avoid any leakage if necessary and the movement of said piston is limited by part 31 screw-connected to body 2.

15 It is obvious that the structure shown may be changed in form and dimensions, without departing from the scope of the invention, and also beam 17 may be replaced by 20 a spring structure to counteract a closing 25 of the valve.

What I claim, is:

1. A pressure reducing valve including a hollow body forming a piston chamber having an inlet and an outlet port, a piston member slidably confined within said chamber for controlling said outlet port, a grooved portion of variable width on said piston member and aligned with said inlet and outlet ports, a by-pass connecting the outlet port with one end of said piston chamber, and means to yieldingly counteract any lateral movement of said piston by back-pressure from the outlet port, said grooved portion on said piston member being of larger width at the side of said outlet port than at the side of said inlet port.

2. A pressure reducing valve including a hollow body forming a piston chamber open at one end, an inlet and outlet port aligned with each other and rectangularly arranged to and for said piston chamber, a piston member slidably confined within said chamber, a grooved portion on said piston member aligned with said inlet and outlet ports, and being of variable width, a by-pass connecting the outlet port with one end of said piston chamber, and means to yieldingly counteract any lateral movement of said piston by back-pressure from the outlet port, the grooved portion on said piston member being of larger width at said outlet port than at the side of said inlet port and the inlet port being of elongated and of larger cross-section than said outlet port to equalize the pressure circumferentially of the piston at the inlet port under all conditions.

In testimony whereof I affix my signature.
ARTHUR HILL.
